UNITED STATES PATENT OFFICE.

WILLIAM RILEY WILCOX, OF MANHATTAN, NEVADA.

PLACER MACHINERY.

Application filed April 1, 1922. Serial No. 548,618.

To all whom it may concern:

Be it known that I, WILLIAM RILEY WILCOX, a citizen of the United States, and a resident of Manhattan, in the county of Nye 5 and State of Nevada, have invented certain new and useful Improvements in Placer Machinery, of which the following is a specification.

This invention relates to placer machinery

10 equally adapted to work dry or wet placers.

The object of the invention is to provide a machine of this character wherein the clots of dirt and of gravel are pulverized and are subjected to a scrubbing action whereby the

15 gold and other placer products are separated from the gangue or other refuse or earthy matter, thus allowing the placer product to be readily caught in the riffles while permitting the refuse or gangue to pass off.

20 Another object is to provide a machine of this character operating in conjunction with a riffle and having means for agitating the riffle to insure and enhance the action thereof.

25 Another object is to provide a device of this character which is simple and durable in construction, reliable and efficient in operation and easy and comparatively inexpensive to manufacture and maintain.

30 Other objects and advantages of the invention reside in certain novel features of construction, combination and arrangement of parts which will be hereinafter more fully described and particularly pointed out in 35 the appended claims, reference being had to the accompanying drawings forming part of this specification, and in which:

Figure 1 is a view in side elevation, illustrating the preferred embodiment of the invention;

Figure 2 is a plan view thereof;

Figure 3 is a view in end elevation, looking toward the discharge end of the machine;

45 Figure 4 is a view in end elevation looking toward the feed or inlet end of the machine;

50 Figure 5 is a detail view in section of a rotatable drum and organized apparatus, parts being shown in elevation for the sake of illustration; and

Figure 6 is a detail perspective view of the traveler and chain pulverizer and scrubber.

55 Referring to the drawings wherein for the sake of illustration is shown the pre-

ferred embodiment of the invention, the numeral 10 designates a supporting frame or base upon which bearing brackets 12 are secured. Grooved rollers 13 are rotatably mounted in the bearing brackets and are preferably provided in pairs, the members of the pairs being arranged on the opposite sides of the supporting frame or base, as shown in the drawings.

60 A rotatable drum 15 is supported for rotation upon the rollers 13 by means of track rings 16 secured to the outer periphery of the drum and operating in the grooves of the rollers 13.

65 Means is provided for rotating the drum 15 and may comprise a driven ring gear or sprocket 17 fixed to the outer periphery of the drum 15 between the track rings 16 and actuated from a hand crank 18 by means 70 of a sprocket gear 19 and sprocket chain 20, the sprocket 19 being fixed to the axis or shaft of the hand crank 18 and this axis or shaft being rotatably journaled in the upper end of standards 21 which upstand from one 75 side of the base for this purpose.

80 A spiral rib 25 is fixed to the inner periphery of the drum 15, as clearly shown in Figure 5, and this spiral rib functions to effect a feed of the material being treated 85 through the drum and also, in conjunction with the pulverizer to be hereinafter described to scrub the material. At the feed or inlet end of the drum an annular plate 26 is arranged and is secured to the inner 90 wall of the drum by means of a flange 27 which is welded, riveted or otherwise secured to the drum. The plate 26 precludes any possibility of the discharge of material from the feed end of the drum and it also 95 serves as a track upon which a traveler, designated generally at 28, is mounted.

This traveler preferably comprises a pair of spaced and curved plates 29 embracing the annular plate 26 and secured to each 100 other and loosely supported upon the annular plate by means of a pair of U-shaped straps 30 having their arms riveted or otherwise suitably fastened to the plates 29. If desired ball bearings or other anti-friction 105 means may be provided between the traveler and the ring 26 such ball bearings may be suitably mounted either upon the straps 30 or plates 29 or upon both. A pulverizer and scrubber, designated generally at 35 is arranged within the drum 15 and coacts with the spiral rib 25 thereof, and this pulverizer 110

and scrubber is constrained to its proper field of action while being free to partake of its necessary movements by means of the traveler 28, as will be presently described.

5 The pulverizer and scrubber is made up of a number of chain lengths, designated at 36, 37 and 38. The chains 36 and 38 have links 39 and 40, respectively, which are engaged with a link 41 of the chain 37 to connect the 10 chains 36 and 38 with the chain 37. A link 42 of the chain 37 is engaged with an eye 43 having swivelled connection with the adjacent plate 29 of the traveler. By securing the pluverizer and scrubber to the 15 traveler by means of the swivelled connection it is permitted to roll over and over in such manner as may be necessary to carry out the pulverizing and scrubbing operation in conjunction with the spiral rub 25 of 20 the drum and then at the same time it is constrained to operate in its proper field by means of the traveler which remains in the position shown in Figure 4 or in substantially such position irrespective of the rotation of the drum 15. The material is fed 25 to the drum from a feed hopper 45 which is agitated from a cam ring 46 integrally formed with or secured to a rotating drum and coacting with an arm 41 connected with 30 the feed hopper, it being understood that the feed hopper is supported so as to yieldably maintain the arm 47 in engagement with the cam 46. The cam serves to periodically urge the hopper away from the drum and 35 gravity serves to return the hopper toward the drum, the resultant agitation or movement effecting the feed of the material.

A riffle, designated generally at 50 is provided which may be of any standard or conventional construction. The riffle is supported upon a pair of posts 51 upstanding from a frame 52 connected with or a part of the base 10. The posts 51 are provided with a series of inclined notches 53 in which 45 the lateral arms 54 of pivoted hangers 55 are adapted to be selectively received, the notches 53 thus affording a vertical adjustment. The lower ends of the hangers 55 are pivotally connected to the riffle, as at 56, 50 and this pivotal connection is preferably arranged to one side of the post as shown in Figure 1, thus inclining the hangers 55 and supporting the riffle so that it tends to swing, under the action of gravity in a counter-clockwise direction as viewed in Figure 1. An arm 58 is secured to the riffle box at the end thereof adjacent to the rotatable drum and the upper end of the arm is angularly offset or hooked, as at 59. The end of the 60 rotatable drum adjacent the riffle 50 carries a cam ring 60 which cooperates with the arm 58 to shake or agitate the riffle box back and forth, the teeth or inclined portions of the cam ring serving to urge the riffle box away 65 from the rotatable drum and gravity serving

to return the riffle box, the action of gravity being positive and effective to accomplish this purpose by reason of the mounting of the box in the manner described. The rotatable drum also carries a second cam ring 70 62 adjacent the cam ring 60 and having its inclined surfaces or teeth arranged in a plane at right angles to the inclined surface of the cam ring 60 as may be readily seen by comparing Figures 1 and 3. The inclined portions or teeth of the ring 62 coact with the angularly extending portion or hook 59 of the arm 58 to rock or oscillate the riffle box 50 about its pivotal connection 56. The rings 60 and 62 thus coact with 75 the arm 58 and hook 59 thereof to utilize the motion of the rotating drum to thoroughly and effectively agitate the riffle box.

The discharge end of the rotating drum, that is the end adjacent the riffle 50, has an 80 annular plate 65 set therein immediately within the ring 62, the annular plate 65 being secured to the drum after the manner in which the plate 26 is secured therein. The inner edge of the annular plate 62 has 85 integrally formed therewith or otherwise connected thereto a discharge funnel 66 which overlies the riffle box and delivers the materials from the rotating drum to the 90 riffle box. A discharge scoop 67 coacts with 95 the funnel 66. The scoop 67 is secured to the drum and rotates therewith and in shape and action is similar to the mold board of a plow, serving to raise the dirt and carry it to the right sufficiently far to discharge it 100 from the drum. The scoop serves not only to discharge the material from the drum in an even and uniform manner but also to measure the amount discharged since it has a predetermined capacity and discharges 105 once for each revolution of the drum.

In operation the drum is rotated by turning the hand crank 18, although it is to be understood that rotation of the drum may be effected from the motor if this is desired. 110 The material to be handled is then fed into the drum through the feed hopper 45. In the drum the chains of the pulverizer and scrubber act upon the dirt and in conjunction with the spiral rib 25 of the drum serve to separate the gold or other placer product from the gangue and refuse matter, thus freeing the placer material so that it may be readily caught on the riffles of the riffle box and so that the refuse or gangue 115 may pass off. When water is used the chain acts as a mixer or puddler to reduce the water and dirt to a thin mud or pulp, allowing the gold and placer product to be easily caught in the riffles of the riffle box. The 120 chains of the pulverizer in carrying out their functions are free to roll over and over as the drum rotates, this freedom being had by virtue of the swivelled connection of the chains with the traveler. At the 125 130

- same time the chains are constrained to rotate in the bottom of the drum since the traveler remains in the same or substantially the same position as shown in Figure 4.
- 5 The material which is discharged from the drum is received in the riffle box and the riffle box is agitated by the rotation of the drum so that it will efficiently operate to catch the gold or placer product.
- 10 I claim:
1. In a machine of the character described, a rotating drum, a spiral rib secured to the inner periphery of said drum and a combined pulverizer and scrubber operating in said drum and comprising a plurality of chains having interconnected links, a plate secured to said drum and constituting a track, and a traveler mounted on said track and having swivelled connection with one of the chains of said pulverizer and scrubber.
  2. In a machine of the character described, a rotatable drum having a track at one end, a traveler operating on said track, a plurality of chains arranged in the drum and a swivelled connection between the chains and the traveler.
  3. In a machine of the character described, a rotatable drum having an annular plate adjacent one end and constituting a track, a traveler operating on said track and including spaced and curved plates arranged on the opposite side of said annular plate, straps spanning said annular
- plate and secured to said curved plates, a plurality of chains arranged in said drum and having interconnected links and a swivelled connection between said chains and said traveler.
4. In a machine of the character described, a rotating drum having a spiral rib secured to its inner periphery, and a combined pulverizer and scrubber comprising a plurality of chains having interconnected links and coacting with the spiral rib.
5. In combination, a rotating drum having a ring comprising a plurality of inclined teeth and a second cam ring also comprising a plurality of inclined teeth, the inclined teeth of the second cam teeth being arranged at right angles with respect to the cam teeth of the first cam ring, a riffle supported for swinging and pivotal motion and an arm carried by the riffle cooperable with the teeth of one of said cam rings, the arm having a hook cooperable with the teeth of the other of said cam rings.
6. In a machine of the character described, a rotatable drum, a spiral rib secured to the inner periphery of the drum, a combined pulverizer and scrubber operating in the drum and comprising a plurality of chains having interconnected links and coacting with the spiral rib of the drum, and a traveler mounted upon the drum and having connection with the combined pulverizer and scrubber.

WILLIAM RILEY WILCOX.
